UNITED STATES PATENT OFFICE.

CHARLES R. ROSEN, OF BUCKINGHAM COURT-HOUSE, VIRGINIA.

PORTABLE FENCE.

SPECIFICATION forming part of Letters Patent No. 236,722, dated January 18, 1881.

Application filed October 20, 1880. (No model.)

To all whom it may concern:

Be it known that I, CHARLES R. ROSEN, a citizen of the United States, residing at Buckingham Court-House, in the county of Buckingham and State of Virginia, have invented 5 certain new and useful Improvements in Portable Fences; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to portable fences in which braces are hinged or pivoted to the posts, so that they may be compactly folded together when the panels are to be packed closely together and removed from place to 20 place, and may be expanded and fastened into the ground at an angle with the posts when the panels are erected and connected together to form a fence.

The object of my invention is to form a cheap, 25 strong, and durable structure, made of few parts, that may be easily put up or taken down at short notice; and the improvement consists in the peculiar construction and arrangement of parts, as will hereinafter appear.

30 In the accompanying drawings, Figure 1 is a perspective view of a single panel, a number of which may be placed together to form my improved fence; Fig. 2, a side elevation of a number of panels connected together, and 35 Fig. 3 a detail showing a modification of the connection between the posts.

The panel is formed of posts A A', of like construction at the ends of the panel, that are connected by rails B, mortised or otherwise 40 permanently secured to the post parallel to each other to be in a horizontal position, and at such length that their ends will not project beyond the posts.

The top or rider rail, C, is secured to the 45 upper ends of the posts in a peculiar manner. Instead of being parallel with the lower rails it is inclined thereto, so that the tenon c upon

one of its ends will pass through the second hole a of one post of a panel, and the other tenon, c', upon its other end will pass through 50 the first or uppermost hole in the next panel, and will be of sufficient length to pass through and somewhat beyond the corresponding or uppermost hole in the adjoining panel, the second hole of which will receive the tenon of 55 the depressed end of its rider or upper and inclined rail, C. The tenon c' of the rider-rail C is rounded to form a journal or pivot, upon which may be fitted the upper ends of braces D D' in such manner that they may be freely 60 turned thereon, so that they may be either expanded at their lower ends to form an angle with the panel, or may be folded parallel with each other and with the adjoining post, so as to be compactly arranged for transportation. 65

Instead of the rider-rails having an elongated rounded tenon, c', at one end only, the other or depressed end of the rail may have a similar tenon, c'', that may pass through the corresponding second hole in the adjoining 70 panel, and form a double connection between the panels.

The braces may be placed one upon the outside and the other upon the inside of the post, as in Fig. 2, or both may be placed upon the 75 inside of its adjacent post, as in Fig. 3, or both may be placed upon one of the elongated tenons, c' or c'', between the posts.

I claim as new—

The combination of two fence-panels having their upright end posts provided each with two apertures, as shown, with inclined rider-rails, the ends of which pass, respectively, through the lower and upper apertures of the uprights of both panels, and with braces pivoted to the rounded tenon of the rider-rails, substantially as described. 85

In testimony whereof I affix my signature in presence of two witnesses.

CHARLES R. ROSEN.

Witnesses:

JAS. A. WRIGHT,
R. H. SPENCER.
